UNITED STATES PATENT OFFICE.

ROBERT C. GROH AND MARTIN A. HANSEN, OF ST. PAUL, MINNESOTA, ASSIGNEES OF ONE-FOURTH TO OLIVER J. DUFRENE AND ONE-FOURTH TO HANS A. SVENDSEN, BOTH OF ST. PAUL, MINNESOTA.

PRIMING-HEATER FOR AUTOMOBILES.

1,265,192.

Specification of Letters Patent.

Patented May 7, 1918.

Application filed January 4, 1915. Serial No. 347.

To all whom it may concern:

Be it known that we, ROBERT C. GROH and MARTIN A. HANSEN, citizens of the United States, residing at St. Paul, in the county 5 of Ramsey and State of Minnesota, have invented certain new and useful Improvements in Priming-Heaters for Automobiles, of which the following is a specification.

Our invention relates to priming heaters 10 for automobiles and has for its object to provide an electric heater device of convenient size adapted to be connected within the intake pipe of an automobile or upon the primer tube of an automobile so that 15 when electricity is supplied thereto the air entering the carburetor, or the priming fluid entering the carburetor, or both, may be preheated to facilitate starting of the automobile.

20 The full objects and advantages of our invention will appear in connection with the detailed description thereof and are particularly pointed out in the claims.

In the drawings, illustrating the application 25 of our invention in one form,—

Figure 1 is a part sectional view of a carburetor and intake pipe showing our heater secured in the intake pipe. Fig. 2 is an enlarged sectional view of the heater along 30 the longitudinal axis thereof. Fig. 3 is a transverse section through the center of the heater. Fig. 4 is a part sectional view of a portion of the device shown in Fig. 2 rotated through ninety degrees. Fig. 5 is a part diagrammatic view showing the device 35 connected on a priming tube running from the fuel supply at the controller-board of the automobile.

As illustrated, the heater comprises an 40 outer shell 10, preferably cylindrical in cross section, of some heat-conducting material, preferably metal, such as aluminum. An inner shell 11, of similar metal, is surrounded by a shell 13 of insulating material, such 45 as mica or asbestos when prepared to be heat-conducting, which must be electrically insulating but heat-conducting. A wire 14 of high resistance for generating heat in an electric circuit is wound spirally on the

shell 14, as shown, being in connection 50 through a metallic header 15 with the outer shell 10. The other end of the heating element is closed by an insulating header 16 through which extends a connector rod or plate 17.

When the heater device is applied to the primer tube, as the tube 18, shown in Fig. 2, extending to the discharge pipe 19 of the carburetor 20, the said primer tube 18 is simply extended through the internal aperture of the inner shell 11, where such tube 18 contacts with the wall of such inner shell. By this means the wire 14, through metal header 15, is placed in electrical communication with the primer tube 18, the other 60 end of said wire connecting through member 17 with a wire 21 which goes to a circuit closer 22 connected with operating battery 23, the other part of the circuit being made through the frame of the automobile in a 70 well-known way.

When it is desired to secure the heater in the intake pipe 24, running to the carburetor 20, said heater is secured to the inner wall of the intake pipe by means of an 75 arm 25 which is fastened by screw bolts or rivets 26 to the shell 10 of the heater; and by similar screw bolts 27 to the wall of the intake pipe.

We claim:

1. An electric priming heater for explosive engines comprising an outer shell, an inner shell, a coil of resistance wire wound about said inner shell and insulated therefrom, a metal head connecting one end of 85 each shell, an insulating head connecting and supporting the other ends of said shells, one end of said coil being attached to and forming a contact with said metallic head and the other end passing through said insulating head and insulated from said other end.

2. An electric heater for explosive engines comprising an inner shell, an insulating sleeve shorter than said shell and passing 90 over the same, an insulating head mounted upon one end of said inner shell adjacent said sleeve, a metallic head mounted upon

the other end of said sleeve, the ends of said inner shell being rolled over said heads to force the same against the sleeve and hold them in place, an outer shell passing over 5 said heads and similarly secured thereto to form an airtight chamber, and a resistance coil wound upon said insulating sleeve between said inner and outer shells.

In testimony whereof we affix our signatures in presence of two witnesses.

**ROBERT C. GROH.
MARTIN A. HANSEN.**
